UNITED STATES PATENT OFFICE

THOMAS MORTIN PRICE, OF ITASCA, TEXAS.

FENCE-STAY.

No. 841,177.

Specification of Letters Patent.

Patented Jan. 15, 1907.

Application filed September 11, 1906. Serial No. 334,129.

To all whom it may concern:

Be it known that I, THOMAS MORTIN PRICE, a citizen of the United States, residing at Itasca, in the county of Hill and State of Texas, have invented a new and useful Fence-Stay, of which the following is a specification.

This invention relates to means for maintaining strands or line-wires of fences in relatively fixed relation to prevent their sagging or being forced apart by the attempted passage of animals between them.

The principal object is to provide a simple article of manufacture that can be readily applied to a fence wherever a stay is deemed desirable, is effective in its bracing or staying action, and can be very cheaply produced.

Two embodiments of the invention are illustrated in the accompanying drawings, wherein—

20 Figure 1 is a view in elevation of a portion of a woven fence, showing one form of stay applied thereto. Fig. 2 is a side elevation of a portion of an ordinary line-wire fence, illustrating a slightly-different form of stay thereon. Fig. 3 is an end view of the stay illustrated in Fig. 2.

Similar reference-numerals designate corresponding parts in all the figures of the drawings.

30 Referring first to the embodiment disclosed in Fig. 1, the fence (designated as a whole by the reference-numeral 4) may be of any desired structure and in itself constitutes no part of the present invention. The stay associated therewith comprises a straight shank 5, of wire, and a retaining-coil 6, extending from end to end of the straight shank and surrounding the same. The lower end of the coil is free from the lower end of the shank.

40 The upper end of said shank is offset, as shown at 7, and the upper end of the coil is connected to the offset.

In the present construction the entire stay is formed from a single piece of wire; but it may be of separate pieces, as disclosed in the embodiment illustrated in Figs. 2 and 3.

50 In using the device, after the fence has been erected, the lower end of the stay is placed upon the top of the fence at the point desired and said stay is rotated, whereupon it will feed downwardly through the fence fabric and intermesh with the strands or wires thereof. When in place, it constitutes an effective stay that will prevent sagging and bulging of the fence, constituting an efficient brace therefor.

The embodiment illustrated in Figs. 2 and 3 is designed more particularly for fences having straight line-wires, though it may be as readily employed with fences of woven wire, if desired. The straight shank (designated 8) is of comparatively heavy wire and, in fact, may be a small rod. Its upper end is offset, as shown at 9. The coil 10 is formed of lighter wire and extends from end to end 65 of the shank 8, surrounding the same, as clearly illustrated. The upper end of the coil 10 is secured to the offset terminal 9 of the shank by being wrapped tightly upon the same, as shown at 11, so that the parts are irreversibly fixed together and are held against relative rotation. This embodiment of the invention is applied in the same manner as the stay first described and when in place constitutes a very effective stay, the heavier 75 shank 8 obviating to a great extent the danger of the stay bending. The lower end of the coil 10 may be coiled about the lower line-wire of the fence as indicated in dotted lines at 12, thus preventing the detachment 80 of the stay by maliciously-disposed persons.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 90 of the invention.

Having thus fully described my invention, what I claim as new, and desire to secure by Letters Patent, is—

1. As an article of manufacture, a fence-stay comprising a substantially straight shank, and a retaining-coil surrounding the shank and irreversibly fixed at one end to the same, said coil and shank being held by their connection against relative rotation. 95

2. As an article of manufacture, a fence-stay comprising a substantially straight shank having an offset terminal, and a retaining-coil surrounding the shank and fixed to the offset terminal thereof, said coil and shank being held by their connection against relative rotation. 105

3. As an article of manufacture, a fence-stay comprising a substantially straight heavy shank having an offset terminal, and a lighter retaining-coil surrounding the shank and fixed to the offset terminal thereof, said 110

coil and shank being held by their connection against relative rotation and having their ends which are opposite to the connection entirely free from each other.

5 4. As an article of manufacture, a fence-stay comprising a straight shank, and a retaining-coil surrounding the shank and coiled from end to end, said coil and shank being connected at one end of the stay only, leaving their other ends free to permit the stay,

when rotated, to feed freely downward through a fence.

In testimony that I claim the foregoing as my own I have hereto affixed my signature in the presence of two witnesses.

THOMAS MORTIN PRICE.
